BY *G. H. Strong.*

ATTORNEY

UNITED STATES PATENT OFFICE.

BERNARD VALENZUELA, OF OAKLAND, CALIFORNIA.

DESIGN FOR A COMBINED BUTTON-HOOK AND BOTTLE-OPENER.

46,382.

Specification for Design.

Patented Sept. 8, 1914.

Application filed May 25, 1914. Serial No. 840,946. Term of patent 14 years.

To all whom it may concern:

Be it known that I, BERNARD VALENZUELA, a citizen of the United States, residing at Oakland, Alameda county, State of California, have invented a new, original, and ornamental Design for a Combined Button-Hook and Bottle-Opener, of which the following is a specification, reference being had to the accompanying drawings, forming part thereof.

Figure 1 is an obverse view. Fig. 2 is a

view looking toward the right end. Fig. 3 is an edge view looking toward the hook opening.

I claim:

The ornamental design for a combined button hook and bottle opener, as shown.

BERNARD VALENZUELA.
